CLAIM

The ornamental design for a non-handed mini-connector, as shown and described.

DESCRIPTION

FIG. 1 is a perspective view of a prior art right handed mini-connector;

FIG. 2 is a perspective view of a prior art left handed mini-connector thereof;

FIG. 3 is a perspective view of a non-handed mini-connector incorporating my new design thereof;

FIG. 4 is a side view of the mini-connector of FIG. 3 with the opposite side view being a mirror image thereof;

FIG. 5 is a right end view of the mini-connector of FIG. 4 thereof;

FIG. 6 is a left end view of the mini-connector of FIG. 4 thereof;

FIG. 7 is a top view thereof; and,

FIG. 8 is bottom view thereof.

The broken lines shown in the nose of the product form no part of the claimed design.
